To all whom it may concern:

Be it known that I, Irving Herman, a citizen of the United States, and residing in the city of Chicago, county of Cook, and State of Illinois, have invented a new, original, and ornamental Design for Seat Cover for Automobiles or Similar Articles, of which the following is the specification, reference being had to the accompanying drawings, forming a part hereof.

Fig. 1 is a front elevation view of my novel seat cover for automobiles showing my design.

Fig. 2 is an end view thereof.

Fig. 3 is an enlarged top plan view of an end section of said cover.

Fig. 4 is an enlarged detailed view of a fragment of the upper tufted panel shown in Fig. 1 and taken in the plane thereof.

The dotted line shown in Fig. 1 is for illustrative purposes only.

I claim:

The ornamental design for a seat cover for automobiles or similar articles, substantially as shown and described.

IRVING HERMAN.
